UNITED STATES PATENT OFFICE.

CLARENCE H. TEALL, OF DETROIT, MICHIGAN.

ROTARY SPARK-GAP MACHINE.

1,250,385.

Specification of Letters Patent. Patented Dec. 18, 1917.

Application filed January 18, 1916. Serial No. 72,780.

To all whom it may concern:

Be it known that I, CLARENCE H. TEALL, a citizen of the United States, residing at Detroit, in the county of Wayne and State 5 of Michigan, have invented certain new and useful Improvements in Rotary Spark-Gap Machines, of which the following is a specification.

This invention relates to a rotary spark 10 gap machine particularly adapted for use in connection with a wireless apparatus.

One object of the present invention resides in the provision of a machine of the above mentioned character, wherein the spark gap 15 is partially closed or diminished by the interposition of a rotating conductor carrying a plurality of sparking points. Thus the gap area is reduced and at the same time this permits an increase in the oscillations or 20 surging of the current delivered to the aerials of the wireless without decreasing the efficiency of the gap.

A further object consists in so arranging the said rotary conductor that it forms part 25 of a rotor of a motor, the stator of which is located within and concentric with said conductor and thus the latter may be driven at any suitable speed by the motor embodied within the device.

With the above and other objects in view, I will now proceed to describe a specific embodiment of my invention and which I have illustrated in the accompanying drawings wherein:

Figure 1 is a side elevation of the machine. Fig. 2 is a transverse section on the line 2-2 of Fig. 1, and

Fig. 3 is a diagrammatic view showing the installation of the device in connection 40 with a wireless apparatus.

In detail:

The device, as shown, comprises a base 1 having mounted thereon the two posts 2 and 3, each of which is insulated from the base 45 1 by an insulating base 4 of suitable thickness. Each of the posts 2 and 3 is provided with a binding post screw 5 receiving a nut 6 by means of which the terminals 50 of the wire may be clamped in place. The upper ends of said posts 2 and 3 are each provided with gap screws 7 carrying spark points 8 and knurled knobs 10 by which the said points 8 may be adjusted to and from each other.

Centrally located with respect to the posts 2 and 3 and transversely positioned with re-

spect to said posts, are the uprights 11 and 12 each insulated from the base 1 by insulating plates 13. Fixed in the upper ends of the uprights 11 and 12 is the hollow shaft 60 14 which carries cores 15 and 16 about which are wound coils 17 and 18. The upright 12 is provided with brush holders 19 and 20, each recessed as shown at 21 to hold brushes 22 behind which are disposed springs 23. 65 One terminal 24 of the coil 17 is connected to one of the brushes 22; whereas, the other terminal 25 of the same coil is connected with one pole of an extraneous source of current; likewise, one terminal 26 of coil 70 18 is connected with the other brush 22; whereas, the other terminal 27 of the same coil is connected with the remaining pole of the same source of current and thus the stator is formed and connected. 75

The rotor comprises a ring 28 carrying radially and inwardly extending iron cores 29 about which is coiled a desired length of wire 30, thus forming a plurality of series wound coils. The said ring 28 is rotatably 80 supported on the hollow shaft 14 by the diametrically positioned members 31 and 32 each of which is insulated from ring 28 by the insulation piece 33; said members are secured in position by screws 34 and are located relatively opposite each other. The member 31 is provided with a centrally located journal box 35 which receives the shaft 14, whereas the member 32 carries the commutator 36 insulated therefrom by the insulating ring 37 and insulated from the shaft 13 by a second insulating ring 38. 90

The commutator 36 comprises two sections 39 and 40, the former of which is in connection with one end 41 of the wire 30, and the latter of which is in connection with the end 42 of wire 30. Thus a motor is formed having an exterior rotor and an interior stator.

Surrounding the ring 28 is an annular 100 insulating ring 43 on the periphery of which is mounted a conducting ring 44 having sparking points 45 equally spaced therearound. Such sparking points 45 travel in the plane of the points 8 during the rotation 105 of the rotor and are but slightly spaced therefrom by the di-electric medium of air separating the points 8 from the rotating conductor, and thus the original gap between the points 8 is decreased in area but 110 not in length by the interposition therein of the rotating conductor 44 and when the

spark jumps from one point 8 to the other it is materially assisted in its jump by the travel of the current through conductor 44 and the discharge takes place between points 8 and points 45 thereby increasing the efficiency of the gap machine.

Referring particularly to Fig. 3, the machine hereinbefore described, is shown in connection with a wireless apparatus where-
10 in the primary circuit P induces a current in the secondary circuit S which will cause a spark to jump between points A and B. During the jump, however, the discharge takes place only through the di-electric me-
15 dium separating points A and B and is con-
veyed by the rotating conductor C and thus the efficiency of the gap is greatly increased and the surging of the current in the aerial D is much more pronounced, thus insuring
20 the sending of plainer messages.

While I have hereinbefore described a specific embodiment of the present invention, it is nevertheless to be understood that in practice, I may resort to such practical
25 modifications as fall within the scope of the invention as defined in the appended claims.

I claim:

1. In a device of the class described, a
spark gap wheel, a pair of uprights, a shaft
30 mounted for rotation in said uprights and
supporting said wheel, a pair of oppositely

disposed brush holders on one of said up-
rights, brushes in said holders, a pair of
coils carried by said wheel, and one terminal
of each of said coils being connected to one
35 of said brushes.

2. In a device of the class described, a
spark gap wheel, a pair of uprights, a shaft
40 mounted for rotation in said uprights and supporting said wheel, a commutator car-
ried by said wheel and surrounding said
shaft, a pair of oppositely disposed brushes
on one of said uprights engaged with said
45 commutator, a pair of coils carried by said
wheel, and one terminal of each coil being
connected to one of said brushes.

3. In a device of the class described, a
spark gap wheel, a pair of diametrically dis-
50 posed members on said wheel, a pair of coils
on said wheel, a pair of uprights, a shaft
supported in said uprights and extending
through said diametrical members, the said
members being insulated from said shaft, a
55 commutator carried by said shaft, and one
terminal of each of said coils being con-
nected to the brushes for said commutator.

In testimony whereof I affix my signature
in presence of two witnesses,

CLARENCE H. TEALL.
